ADJUSTABLE SCREEN DOOR GRILLE

Robert H. Hutchinson, Dallas, Tex.

Application April 22, 1950, Serial No. 157,429

3 Claims. (Cl. 160—161)

1

This invention relates to screen door grilles and more particularly to adjusting features of this type of grille.

A popular type of protective grille for screen doors is composed of intercrossed straps of metal, pivoted at their intersections and whose ends are formed into ornamental scrolls. One disadvantage however in this type of grille lies in the fact that adjustment of the grille in one dimension, as permitted through the pivotal interconnection of its component parts will result in a corresponding change in the other dimension. In fitting a grille to a screen door frame where the required expansion in a vertical direction is but slight, it has been the practice to partially unroll the uppermost scrolls of the grille until sufficient height is gained to reach the cross-bar of the screen door frame. On the other hand, a limited increase in height is obtained in the manner described in applicant's U. S. Letters Patent No. 2,325,402 in which extra arms are pivoted intermediate their ends to the upper ends of certain of the intercrossing straps of the grille. These methods of obtaining height adjustment of the grilles have proved to be inadequate in many cases.

The principal object of the invention is to provide a screen door grille consisting of the usual intercrossed and pivoted straps having scrolled ends but certain of the straps are shaped to define receptacles midway between the sides of the grille at its top and bottom, in each of which is mounted for longitudinal sliding displacement, an auxiliary securing means for the grille which not only prevents flapping of the grille at the top and bottom but also lends to the ornamental appearance thereof. Moreover, by virtue of the invention, a grille so equipped will find wider adaptation since it may conveniently and quickly be adjusted in one direction with compensation for like adjustment in a transverse direction without disturbing the ornamental appearance of the grille.

Other objects will appear as the description proceeds, taken in connection with the accompanying drawing, wherein:

Figure 1 is an elevational view of a screen door grille constructed according to the invention.

Figure 2 is a fragmentary view showing the form of clamp employed to hold the grille parts together, and

Figures 3, 4 and 5 show schematically various shapes assumed by the grille to illustrate the adaptation thereto of the adjusting means of the invention.

Continuing with a more detailed description of the invention, reference numeral 10 denotes a

2

pair of metal straps or bars forming a substantially X-shaped design in the center of the grille and to these straps are pivoted at 11, intercrossing straps 12. The ends of straps 10 are coiled into scrolls 13, as are the adjacent ends of the straps 12 whose scrolls 14, together with scrolls 13, are screwed to the upright members 15 of a screen door frame.

Conventional grilles constructed with intercrossed and pivoted straps are capable of horizontal and vertical adjustment by reason of the relatively pivotal displacement of the straps. However, extension in a longitudinal direction produces a corresponding contraction in a horizontal direction and vice versa, hence to establish anchorage at the top and bottom of the grille, the invention provides the arrangement shown and while such arrangement precludes free pivotal displacement of the straps 10 and 12, they can nevertheless be so displaced for expansive and contractive adjustments of the grille by bending the straps 12 at points *a* (Fig. 1). This is done usually to change the horizontal dimension of the grille since the invention, to be described presently, compensates for any deficiency in the vertical dimension.

The upper and lower straps 12 are convergent towards a point midway between the upper and lower ends of the intercrossing straps 10 and at points *a* in the straps 12, the end portions *b* thereof are turned into substantial parallelism but are spaced apart to accommodate for sliding movement therebetween, a pair of straps 16. The end portions *b* of straps 12 are secured in the described relationship with straps 16 by means of lengths of metal straps formed into collars 17 which embrace the straps 12 and 16 in clamping engagement in the manner shown in Figure 2 in which, it will be observed, the confronting ends of the strap forming the collar are spaced apart to define a slot 18 to receive the bit of a screw driver or like instrument for expanding the collar, thus to enable the straps 16 to be slid freely between the flanking end portions *b* of straps 12.

The end portions *b* of straps 12 are bowed outwardly between the clamps 17 at the top and bottom of the grille. This is to minimize frictional engagement between the portions *b* and straps 16 when it is desired to move the latter longitudinally. The extremities of straps 12 are formed into ornamental flat scrolls 19 both at the top and bottom of the grille to carry out the symmetrical design of the grille.

In like manner, the inner ends of the straps 16 are formed into scrolls 20 while the outer ends thereof are arcuated as at 21 and are apertured

to receive screws by which they are secured to the horizontal portions 22 of the screen door frame.

It is evident from the foregoing that in order to compensate for any loss in the vertical dimension of the grille as a result of horizontal extension thereof, it is necessary only to expand the collars 17 either at the top or bottom or both, by inserting a tool in the slot 18 thereof. This permits the straps 16 to be slid outwardly until their arcuated outer ends are brought up against the horizontal portions 22 of the screen or to a predetermined measurement, whereupon the clamps are again closed tightly on the straps by striking them a blow with a hammer. The grille, now properly adjusted to the screen frame may be secured therein by inserting screws in holes made in each of the scrolls 13, 14 and 21.

Manifestly, the construction as shown and described is capable of some modification and such modification as may be construed to fall within the scope and meaning of the appended claims is also considered to be within the spirit and intent of the invention.

What is claimed is:

1. In a grille adapted for disposition in a screen door frame, a plurality of intercrossing straps of malleable material connected together at their intersections for relative pivotal displacement, selected pairs of said straps having their ends bent into relative parallelism and defining angles at the bends which are changeable in accordance with the relative displacement of said straps, an adjusting member comprising a pair of parallel straps disposed between the parallel ends of said selected pair of straps for vertical sliding displacement, spaced apart means embracing the pairs of straps capable of expansion and contraction for respectively releasing and binding said pairs of straps and means for securing the outer ends of each of said straps to said screen door frame.

2. In a grille adapted for disposition in a screen

door frame, a plurality of intercrossing straps of bendable material connected together at their intersections for relative pivotal displacement, at least two of said straps having their ends bent at angles disposing said ends in relative parallelism but which angles are changeable to yield to said pivotal displacement of said straps, expandable collars embracing the parallel portions of said straps in spaced apart relationship, means disposed for longitudinal sliding adjustment between said parallel portions to compensate for contraction of said grille in one plane caused by its expansion in a right angular plane and means for affixing the outer ends of said straps and said adjustable means to said screen door frame.

3. In a grille composed of intercrossing and relatively pivoted straps adapted for vertical and horizontal expansion and contraction to adapt the same to a screen door frame, means adapted to compensate for variations in the height of said grille as a direct result of variations in the width thereof, said means comprising a pair of straps connected for vertical sliding displacement between convergent parallel ends of selected straps of said grille at the top and bottom thereof to vary the effective length of said grille irrespective of the width thereof said relatively pivoted straps being bendable at points below their parallel ends to yield to adjustments in the width and length of said grille and means for securing the outer ends of said pivoted and slidable straps to said screen door frame.
